FUSE CONSTRUCTION

Alwin G. Steinmayer, Milwaukee, Wis., assignor
to Line Material Company, South Milwaukee,
Wis., a corporation of Delaware

Application April 10, 1936, Serial No. 73,652

2 Claims. (Cl. 200—117)

This invention relates to a fuse construction.

Objects of this invention are to provide a fuse construction which is so made that when the fuse link is ruptured, a wide separation of the parts is automatically obtained, in which any remaining unburned portions of the fuse link, such as the leaders for instance, are thrown or discharged from the device and are, therefore, not left hanging in space.

10 Further objects are to provide a fuse construction which, as stated, provides for the automatic separation of the elements thereof when the fuse is ruptured, but which nevertheless is extremely simple in its construction and has a very small 15 number of parts, and which may be cheaply produced and readily installed.

Further objects are to provide a construction which may be readily refused in a simple and easy manner, as, for instance, by the use of a 20 switch stick without requiring the operator to handle any live parts.

A further object is to provide a fuse construction in which leakage is prevented and a long 25 surface path is interposed between the support and both of the elements or terminal members, and in which the arc is confined to a definite point preferably in an insulating casing so that the arcing over between terminal members even under severe conditions is minimized, and in 30 which the actual fusing takes place at a point spaced a material distance from the insulating body portion so that there is no chance of the formation of a conducting or carbonized or metallic deposit film on the insulating body portion.

35 An embodiment of the invention is shown in the accompanying drawing, in which:

Figure 1 is a side elevation of the device with parts in section showing the supporting elements thereof or terminal members in full lines in their 40 normal position and showing such elements in their open position in dotted lines.

Figure 2 is a sectional view on the line 2—2 of Figure 1.

Referring to the drawing, it will be seen that 45 a porcelain or other insulating body portion or main member 1 is provided and is preferably equipped with a plurality of petticoats or skirts between the ends thereof and the central reduced portion 2. The supporting member may take 50 any desired form and is preferably arranged as a clamp 3 which grips around the reduced central section 2 and which is attached to a supporting bracket 4 adapted to be carried by a pole arm, for instance.

55 The ends of the insulating body portion 1 are

also provided with reduced cylindrical portions 5 terminating in end flanges 6. A pair of clamping straps 7 and 8 of approximately semi-circular shape are positioned about each reduced end portion 5 and are drawn together by means of 5 the bolts 9.

The terminal members may consist of spring wire looped members 10 and 11. For instance, the member 10 may be the upper member and the member 11 the lower, as shown in Figure 1. These 10 looped wire supporting members or terminal members 10 and 11 may be formed of any suitable material, such, for example, as phosphor bronze. They have their ends 12 and 13 extending through apertures formed in the clamping members 7 and 8 and, as will be seen from Figure 2, when the clamping members are drawn tight, the arms of the U-shaped wire spring terminal members 10 and 11 are drawn into binding contact with the reduced portion 5 of the porcelain insulator. Obviously any other means for clamping the members 10 and 11 to the ends of the porcelain body portion may be employed.

It is obvious that at least one of the arms 10 and 11 must be resilient, though it is preferable to 25 have both of them so. Nevertheless one alone may be resilient and the other may be rigid.

The members 10 and 11 are U-shaped or V-shaped, as may be seen from Figure 2, and are 30 respectively provided in their arm sections with coiled portions 14 and 15 to increase their resilience. The folded ends or doubled ends of the spring arms 10 and 11 are provided with hook portions 16 and 17 about which the looped ends 35 of a fuse link are positioned.

The fuse link may consist of a fusible section 18 positioned within an insulating, non-combustible sheath or sleeve 19 and terminating in looped end portions or leaders 20. These looped portions 20 are hooked over the hook portions 16 40 and 17.

Any suitable connecting means may be provided, for instance, the connectors 21 and 22 by means of which the conductors 23 and 24 may be electrically connected to the arms 10 and 11 respectively.

When an overload occurs, the fusible portion of the fuse link is ruptured and the arc is confined within the sleeve 19. However, the spring arms or terminal members 10 and 11 quickly pull 50 the remaining or unburned sections of the fuse link apart and these sections are thrown or flipped off from the arms 10 and 11, thereby discharging the remaining portion of the fuse link from the device.

Even a slowly applied overload results in a quick breaking of the circuit.

Further it is to be noted that there is no likelihood of an arc being established between the 5 terminal members as the arc is confined within the sleeve 19 on the one hand and, on the other hand, as a quick and wide separation of the parts is provided.

In refusing the device it is a simple matter to 10 carry the fuse on the end of a fuse stick or switch stick and hook one of the looped portions into the corresponding hooked portion of its terminal member. Thereafter such terminal member may be deflected until the other end of the fuse link 15 can be hooked over the hooked portion of the other terminal member. Thereafter the switch stick is removed and the spring arms or terminal members adjust themselves, as shown in full lines in Figure 1.

20 It is apparent that by having the lower terminal member project laterally a lesser distance than the upper terminal member that in refusing it is easier for the lineman to refuse the device than if they both projected the same distance or if the 25 upper terminal member projected a lesser distance than the lower terminal member, for when the fuse link is attached to the lower terminal member, it may then be attached to the upper terminal member although the switch stick is 30 in a substantially vertical position for there is no chance of the switch stick engaging the lower terminal member. Additionally, when the device operates, it is apparent that there is more chance for the looped ends of the fuse link to detach 35 themselves from both the upper terminal member and the lower terminal member than would be the case if the device were otherwise arranged, for example as pointed out above, for during the outward motion of the terminal members each 40 portion of the fuse link tends to swing into a vertical position and rock outwardly from the hooked ends and will thus clear the hooked ends.

45 It will be seen that this fuse construction provides a wide separation when the fuse blows but nevertheless, though it has this automatic action, it is of extremely simple construction and may be cheaply manufactured and easily installed.

Further, as pointed out hereinabove, refusing

of the device is simple and may be quickly performed without endangering the lineman as he does not come in contact with any live parts whatsoever during this refusing operation.

Additionally, it is to be noted that actual fusing occurs at a point widely spaced from the insulating body portion and consequently no carbonized film or film due to a metallic deposit can be formed on the body portion. Consequently the body portion retains its full characteristic as 10 an insulator no matter how many successive operations of fusing and refusing have taken place.

Although this invention has been described in considerable detail, it is to be understood that such description is intended as illustrative rather than limiting, as the invention may be variously embodied and is to be interpreted as claimed.

I claim:

1. A circuit interrupting device comprising an insulating body portion having upper and lower 20 ends, upper and lower spring wire terminal members having spaced legs located on opposite sides of the upper and lower ends of the body portion and having hooked outer ends and intermediate diverging portions from adjacent the hooked 25 ends to adjacent the body portion, clamping members encircling the upper and lower ends of the body portion and drawing the spaced legs of the terminal members into binding engagement with said body portion, and a fuse link having looped 30 ends hooked over the hooked ends of said terminal members and tensioned by said terminal members.

2. In a circuit interrupting device including an insulator body having upper and lower end portions cylindrical in cross-section, the combination with a pair of arcuate clamping members on each end portion and each having clamping ears projecting laterally of the body and paralleling adjacent corresponding ears on the other of 40 said members, each of said members being apertured adjacent said ears, of upper and lower resilient wire terminal members having spaced legs located on opposite sides of said end portions and extending through said apertures, and 45 clamping means on said ears holding said members in binding engagement with said body to thereby clamp said legs to said body.

ALWIN G. STEINMAYER.
